[57] CLAIM

The ornamental design for a racquet display case, as shown and described.

DESCRIPTION

FIG. 1 is a side elevational view of a racquet display case showing my new design, the opposite side being a mirror image thereof;

FIG. 2 is a top plan view thereof;

FIG. 3 is a bottom plan view thereof;

FIG. 4 is an end elevational view thereof;

FIG. 5 is a side elevational view of a modified form of the racquet display case, the opposite side being a mirror image thereof;

FIG. 6 is a top plan view of FIG. 5;

FIG. 7 is a bottom plan view of FIG. 5;

FIG. 8 is an end elevational view thereof.
